UNITED STATES PATENT OFFICE

160,739

TOILET TISSUE HOLDER

Gregg Ransburg, Indianapolis, Ind., assignor to
Harper J. Ransburg Co., Inc., Indianapolis,
Ind., a corporation of Indiana

Application April 21, 1950, Serial No. 9,405

Term of patent 14 years

(Cl. D4—3)

To all whom it may concern:

Be it known that I, Gregg Ransburg, a citizen of the United States, residing at Indianapolis, Indiana, have invented a new, original, and ornamental Design for a Toilet Tissue Holder, of which the following is a specification, reference being had to the accompanying drawing, forming a part thereof.

Fig. 1 is an isometric view of a toilet tissue holder, showing my new design;

Fig. 2 is another isometric view as seen from below.

I claim:

The ornamental design for a toilet tissue holder, as shown.

GREGG RANSBURG.
